UNITED STATES PATENT OFFICE.

WILLIAM HOUGHTON, OF BATH, MAINE.

COMBINED MARKING-PEG AND CENTER-PUNCH.

No. 824,867.

Specification of Letters Patent.

Patented July 3, 1906.

Application filed February 15, 1906. Serial No. 301,296.

To all whom it may concern:

Be it known that I, WILLIAM HOUGHTON, a citizen of the United States, residing at Bath, in the county of Sagadahoc and State of Maine, have invented certain new and useful Improvements in a Combined Marking-Peg and Center-Punch; and I do declare the following to be a full, clear, and exact description of the invention, such as will enable others skilled in the art to which it appertains to make and use the same.

This invention relates to improvements in combined marking-pegs and center-punches.

The object of the invention is to provide a device of this character by means of which rivet or other holes may be transferred from a templet or pattern and accurately centered on the sheet or plate to be drilled or punched out.

With the above and other objects in view the invention consists of certain novel features of construction, combination, and arrangement of parts, as will be hereinafter described and claimed.

In the accompanying drawings, Figure 1 is a vertical sectional view through the outer tube or casing of the tool, showing the punch in a retracted position. Fig. 2 is a similar view showing the punch in a projected position. Fig. 3 is a detail side view of the punch, and Fig. 4 is a horizontal sectional view taken on the line 4-4 in Fig. 2.

Referring more particularly to the drawings, 1 denotes the punch, which is preferably cylindrical in form and is provided on one end with the usual punching-point 2. Substantially midway between the ends of the punch is arranged a transversely-disposed aperture 3, through which is inserted 40 the stop-pin 4, the ends of which project slightly beyond the sides of the punch, as shown. A short distance below the aperture 3 and at right angles thereto is formed a second aperture 5, in which is placed a stop-pin 6, which projects slightly beyond the sides of the punch.

Arranged on the punch 1 is a marking-peg 7, said peg being here shown in the form of a cylindrical tube or sleeve. In the upper end 50 of the tubular marking-peg 7 is arranged a guide-collar 8, said collar being held in position in the tube by means of a set-screw 9, which is passed through the side of the tube and enters the collar 8, as shown. In the lower end of the collar 8 at diametrically op-

posite points are arranged vertically-disposed slots or recesses 10, which when the punch is in a retracted position are adapted to be engaged by the projecting ends of the upper stop-pin 4, arranged in said punch. 60 In the lower edge of the collar 8 at right angles to the slots or recesses 10 are formed diametrically opposite notches 12, which are adapted to be engaged by the projecting ends of the pin 4 when the punch is in a projected 65 position, the punch being slightly turned as the same is projected to cause the ends of the pin to align with the notches 12, as will be understood.

Adjacent to the lower end of the tubular marking-peg 7 is a guide-collar 13, said collar being secured in place by means of a set-screw 14. Arranged on the punch 1 below the lower pin 6, with which the same is engaged, is a collar 15, between which and the guide-collar 75 13 is arranged a coil-spring 16, the tension of which is normally exerted to retract the punch 1 to the position shown in Fig. 1 of the drawings.

In using the tool as a marking-peg the 80 punch is in a retracted position, as shown in Fig. 1, thus permitting the lower end of the marking-peg to be inserted through the holes in the templet or pattern which has been previously laid on the work, thus marking said 85 holes on the plate or sheet beneath the templet, it being understood that the end of said peg 7 is previously dipped into a suitable marking solution. When the peg is to be used to transfer holes in the templet by center-punch marks, the centers of said holes may be accurately marked by striking the upper end of the punch with a hammer or mallet, which will force the same downwardly against the tension of the spring 16, causing 90 the point to mark the center of the holes. When it is desired to use the punch without the marking-peg, the punch is projected beyond the lower end of the latter and locked in 95 said projected position by turning the punch 100 to bring the projecting ends of the pin into engagement with the notches 12 in the lower end of the guide-collar 8, as clearly shown in Fig. 2 of the drawings.

From the foregoing description, taken in 105 connection with the accompanying drawings, the construction and operation of the invention will be readily understood without requiring a more extended explanation.

Various changes in the form, proportion, 110

and the minor details of construction may be resorted to without departing from the principle or sacrificing any of the advantages of this invention as defined by the appended 5 claims.

Having thus described my invention, what I claim as new, and desire to secure by Letters Patent, is—

1. In a device of the character described, 10 the combination with a sleeve or tube, of a punch slidably mounted therein, a slotted guide-collar arranged in the upper end of said tube, stop-pins arranged in said punch to engage the slots in said guide-collar, and a 15 spring to retract said punch, substantially as described.

2. In a device of the character described, the combination with a sleeve or tube, of a punch slidably mounted therein, an upper 20 guide-collar arranged in the upper end of said tube, said collar having formed in its lower end vertically-disposed slots and notches arranged at diametrically opposite points, means to secure said collar in said sleeve, up- 25 per and lower horizontally-disposed pins arranged at right angles in said punch to engage the slots and notches in said collar, a retracting-spring arranged on said punch, and

means to hold said spring in place, substantially as described.

3. In a device of the character described, the combination with a sleeve or tube, of a punch slidably mounted therein, an upper guide-collar arranged in the upper end of said tube, said collar having formed in its lower end vertically-disposed slots and notches arranged at diametrically opposite points, a set-screw to hold said collar in place in said tube, upper and lower horizontally-disposed pins arranged at right angles in and projecting 40 from the sides of said punch to engage the slots and notches in said collar, a guide-collar fixed in the lower end of said tube, a collar loosely mounted on said punch below said lower pin and a coiled retracting-spring ar- 45 ranged on said punch between said fixed lower collar and said loose collar, substantially as described.

In testimony whereof I have hereunto set my hand in presence of two subscribing wit- 50 nesses.

WILLIAM HOUGHTON.
